UNITED STATES PATENT OFFICE.

THOMAS J. NEWBERRY AND JOHN V. ERICSON, OF CHICAGO, ILLINOIS.

GONDOLA FREIGHT-CAR.

SPECIFICATION forming part of Letters Patent No. 695,623, dated March 18, 1902.

Application filed December 20, 1901. Serial No. 86,700. (No model.)

To all whom it may concern:

Be it known that we, THOMAS J. NEWBERRY and JOHN V. ERICSON, citizens of the United States, residing at Chicago, in the county of Cook and State of Illinois, have invented certain new and useful Improvements in Gondola Freight-Cars, which are fully set forth in the following specification, reference being had to the accompanying drawings, forming

10 a part hereof, and in which—

Figure 1 shows our said new car in front elevation, of which the right-hand half shows an exterior view and the other half an interior view, with some parts in section and the 15 various operating parts in both broken and entire outlines for the purpose of showing their manner of operation. Fig. 2 shows our said device in plan view with some of the doors removed, some open, and some closed. Fig. 3 shows our car in side elevation with a fragment thereof in section between one pair of frames A and the other parts provided with compound doors, shown closed at other sections. Fig. 4 shows a front elevation of a 20 fragment of a transverse frame A of the car-body with a hinged discharging-bottom or trap-door in closed position, also in open position in broken outlines. Fig. 5 shows a front elevation of a fragment of a transverse frame 25 similar to that shown in Fig. 4, having a like hinged bottom, but locked by a different kind of mechanism. Fig. 6 shows an entire transverse frame in front elevation on a smaller scale, together with a vertical longitudinal section taken through its center. Fig. 30 7 shows a right-hand end bar of any of said transverse frames provided with a locking mechanism for the discharging-doors g. Fig. 8 shows in side elevation mechanism to operate the lever locking and releasing mechanism shown in Figs. 1, 3, 5, and 7. Fig. 9 shows in fragments and in part Fig. 8 in plan view.

Like reference-letters denote like parts 45 throughout all the figures.

The object of our invention is to produce a gondola freight-car of steel construction and without the usual sills, cross-beams, and the like for floor-supports; but instead thereof 50 the floor part of our car consists of one or more longitudinal beams of either the I or U pattern in cross-section and preferably two

such beams and that of the U pattern, as shown in Fig. 1, on and around which we build the bottom of our gondola. Said bottom is preferably of cylindrical section, as shown, because of the most desirable form both for strength and convenience of construction, also to secure by our said form a lower center of gravity for the load than is obtained in the usual form of construction having either flat or longitudinally-arched floors; and our invention also consists in dividing the box or body of our car into sections or parts provided with side doors, 65 either single or compound, from which the load may be discharged in suitable quantities, and other advantages hereinafter to be set forth. To attain said desirable ends, we construct our improved gondola substantially 70 as follows, namely:

In the drawings, in Fig. 1, are shown two U-beams b, having their plain sides facing toward the center line and extending from end to end of the car-body. Between said beams b is thus provided a convenient place for the draw-head and other draft-rigging. Over the tops of the beams b is secured a cylindrical section c of sheet-steel to form the fixed bottom of the gondola box f. The outer 80 edges of said section c extend below the tops of the wheels, as near as may be to their axles, and under said beams b is secured a bracing-plate d, which rises upward from the foot of each beam to meet the cylindrical bottom and to which its ends are attached. Said bracing is shown in end view in broken lines in Fig. 3, and in this case is shown over the saddle-bar a of the truck; but there may be as many such braces as may be deemed 90 necessary, or, in fact, said part d may be extended both ways to the full length of the cylinder c, and thus form an additional strengthening to the bottom c. The outer edges p of the cylinder c are turned out at 95 about right angles to the flanges n or parallel to the ends of said flanges, as shown at p in Figs. 1, 4, 5, 6, and 7. By means of said cylindrical arch and beams thereto there is formed a very strong yet light gondola bottom.

The frames A consist of two vertical stays e, T-shaped in cross-section, which are connected by a web o', having a top flange n'

and an arched bottom flange o , fitting on the cylinder c and to which said flange is secured. A bottom n^2 is laid either on or between the flanges n' , and said bottom has openings provided with trap-doors m , hinged at q , as shown in Figs. 1, 2, 4, and 5, and said doors may be held up at their free ends by a hook k^2 , Fig. 4, provided with a lever k' , which is held in its place by a pivoted stop k^3 . The preceding form of holding mechanism for this trap-door is used when the load is to be carried on the level bottom n^2 . Said trap-doors may be lowered into the position indicated in broken lines in Figs. 1 and 5 when the side doors g form a part of the structure. In the latter case when the doors g are opened the doors m drop from the bracket g^2 and the load is discharged, or the trap-doors may either be omitted entirely and the load carried on the cylinder c when the side doors g are used. In Fig. 2 the trap-doors m are shown taken out of the first sectional spaces, and the right and left hand parts of the cylinder c are shown. In the other sectional parts the doors m are shown closed. Said side doors g may also be formed into compound doors by the use of smaller or secondary doors h over openings through said primary doors, through which small portions of the load of their sections, into which our car-body is divided by our cross-frames A, may be let out, as when it may be desired to load only a small wagon, and larger loads may be let out by using both small doors together or in part only, and finally all the doors g may be opened for the discharge of the entire load on either one or both sides of the car. Said doors g are hinged at l and their opposite edges are held by any suitable means, as by hooks j on a hinge j' , secured on the under side of the bottom c . To said hooks j are secured operating-levers k , whose free end is held and released by a reciprocable bolt r^5 , secured to the vertical rib of the stay, as shown in Figs. 5 and 7. Said bolt r^5 is connected to a bell-crank lever r^4 , which in turn is connected to a reciprocable bar r^3 , of which one end is connected to an arm r^2 on the end of a shaft r at one end of the car-body, and to said shaft is secured an operating-lever r' , by means of which and in one movement thereof all the doors g , either on one or both sides of the car, may be opened simultaneously, as may be desired. The small doors h on said doors g are here shown locked with a button i . The stays e are bent at about the floor-level n^2 to project inward, as shown at e' , and the box sides of the box f are held by said two parts e and e' . The broken lines

t in Fig. 1 are to indicate how the central part of the bottom n^2 may be raised for the more complete discharge of its load through the bottom of the car. The flanges n' are but a continuation of the flanges n of the stays e , forming a part of the web o' of the frame A.

What we claim is—

1. The combination with longitudinally central beams, extending from truck to truck, of a cylindrical bottom attached directly to said beams, substantially as specified.
2. The combination with longitudinally central beams, extending from truck to truck, of a cylindrical car-bottom, secured directly to said beams, having its side edges below the wheel-tops, substantially as specified.
3. The combination with longitudinally central beams, extending from truck to truck, and a cylindrical car-body bottom, attached directly to said beams, having its edges below the wheel-tops, of a car-body having discharging-doors with free edges locked to said side edges, substantially as specified.
4. The combination with longitudinally central beams, extending from truck to truck, and a cylindrical car-body bottom, attached directly to said beams, having its side edges below the wheel-tops, of a car-body having discharging-doors whereof their free edges are locked to said side edges, and means to lock said doors to said edges, substantially as specified.
5. The combination with a cylindrical car-bottom having its side edges below the wheel-tops, of a car-body with compound discharging-doors immediately above said edges, substantially as specified.
6. The combination with a cylindrical car-body bottom, of a flat bottom with closable openings through it above said cylindrical bottom, substantially as specified.
7. The combination with a car-body having a cylindrical bottom, of a flat bottom above said cylindrical bottom having closable passages, side doors to hold said closures and means to operate said doors, substantially as specified.
8. The combination with a car-body having a cylindrical bottom and transverse frames dividing said car-body into sections, of discharging-doors immediately above the edges of said bottom, substantially as specified.
